(57) **CLAIM**

We claim the ornamental design for a mouse pad, as shown and described.

DESCRIPTION

FIG. 1 is a perspective view of a mouse pad in accordance with the present invention.

FIG. 2 is a top view of the mouse pad illustrated in FIG. 1. FIG. 3 is a bottom view of the mouse pad illustrated in FIG. 1.

FIG. 4 is a front view of the mouse pad illustrated in FIG. 1, the rear view being identical; and,

FIG. 5 is a side view of the mouse pad illustrated in FIG. 1, the opposite side view being identical.

The cross hatching shown in FIGS. 1, 2 represent texture and covers the entire central surface.
